GAMEBOARD FOR PARLOR GAMES

Bill E. Taylor, 617 S. Quincy, Enid, Okla. 73701

Filed Feb. 26, 1971, Ser. No. 119,436

Term of patent 14 years

Int. Cl. D21—01

U.S. Cl. D34—5

FIG. 1 is a top plan view of the gameboard, showing my design;

FIG. 2 is a bottom plan view of the gameboard design;

FIG. 3 is a side elevational view of the gameboard design, showing either the right or the left side; and

FIG. 4 is an end elevational view of the gameboard design, showing either the top or the bottom end.

I claim:

The ornamental design for a gameboard for parlor games, as shown and described.
